The ornamental design for binoculars, as shown and described.

DESCRIPTION

FIG. 1 is a front elevational view of binoculars showing a first embodiment of our new design, with lens barrels in the normal positions;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a perspective view thereof;

FIG. 8 is a front elevational view thereof, with lens barrels in the folded positions;

FIG. 9 is a top plan view of a second embodiment of the design, with lens barrels in the normal positions, and which differs from the first embodiment only with respect to the length of the lens barrels;

FIG. 10 is a bottom plan view thereof; and,

FIG. 11 is a sectional view thereof taken along the lines 11—11 on FIG. 3.
